UNITED STATES PATENT OFFICE

2,036,797

HYDRAULIC OPERATING DEVICE

Theodore W. Driesch, Schenectady, N. Y., assignor to General Electric Company, a corporation of New York

Application June 12, 1934, Serial No. 730,237

11 Claims. (Cl. 60—52)

This invention relates to hydraulic operating mechanism, more particularly to hydraulic mechanism in which a motor driven impeller pump immersed in the fluid within a container is utilized to produce a differential fluid pressure on opposite sides of a piston to effect movement thereof and it has for an object the provision of a simple reliable and improved device of this character.

More specifically this invention relates to hydraulic operating mechanism of the type in which fluid pressure is utilized to effect movement of the piston in both directions without reversing the rotation of the pump driving motor and a further object of the invention is the provision of a compact, double-acting hydraulic operator in which the pump and the control mechanism for reversing the movement of the piston are all mounted within the operating cylinder. In carrying this invention into effect in one form thereof, the impeller pump and the piston are both mounted within the operating cylinders with a partition between them, and rotary valve means surrounding the pump cooperates with passages in the partition means for controlling the direction of the pressure acting on the piston.

For a better and more complete understanding of the invention, reference should now be had to the following specification and to the accompanying drawings in which Fig. 1 is an elevation taken in section on the line 1—1 of Fig. 4 viewed in the directions of the arrows with certain parts broken away; Fig. 2 is a fractional view in elevation taken in section on the line 2—2 of Fig. 3, viewed in the directions of the arrows, with certain parts broken away for illustrating an operating condition of the control means; Figs. 3 and 4 are plan views of the device of Fig. 1 partly in section and with the piston removed and certain parts broken away illustrating different operating positions of the control mechanism; Fig. 5 is an exploded view in perspective of the impeller pump and control mechanism of the device of Fig. 1; and Fig. 6 is a view in elevation, partly in section of a modification.

Referring now to the drawings, a cylindrical fluid container 10 is provided with a cover plate 11 upon which an electric driving motor 12 is vertically mounted so that its shaft 13 extends beneath the cover plate into the container. The cover plate 11 is constructed to provide an integral supporting platform 14 extending beneath the top of the container 10.

The cylindrical container 10 is filled with a

suitable fluid medium, such for example as oil, to a point which is preferably substantially level with the platform 14. A piston 15 is arranged within the cylindrical casing 10 for vertical movement, and the movement of the piston is transmitted to an external load by means of a pair of connecting rods 16. The lower ends of these connecting rods 16 are secured by suitable fastening means to the piston 15 whilst the upper ends of these connecting rods extend through the cover plate 11 and are secured to a cross-head 17 which is adapted to be connected to any suitable load. At the bottom of the container, is an impeller pump illustrated as comprising a housing 18 within which an impeller 19 is rotatably mounted. The housing 18 is preferably formed with upper and lower plates 20 and 21 which are spaced apart by a circumferential wall member 22 to provide a pressure chamber 23 for radial exhaust of the impeller 19. This structure is clearly visible in the exploded view of Fig. 5. The housing also comprises upper and lower hub members 24 and 25 respectively, which are preferably formed integrally with the top and bottom plates 20 and 21 respectively.

As shown, the top hub portion 24 is provided with a plurality of axial intake ports 26 and a circumferential row of intake ports 27. The lower hub member 25 is provided with an upper circumferential row of intake ports 28 and a lower circumferential row of intake ports 29. Likewise the top plate 20 of the housing is provided with a plurality of axial discharge ports 30 and the circumferential wall member 22 is provided with a plurality of circumferential discharge ports 31.

Within the fluid container 10 is a cylindrical tank 32, the outside diameter of which is smaller than the inside diameter of the fluid container 10 so that the wall of the inside tank 32 is spaced from the wall of the external container 10. The inside tank 32 serves the double function of providing a cylinder within which the piston 15 slides and of providing a passageway 33 leading from the exhaust of the pump to the space above the piston 15. This inside tank 32 is preferably formed by an upper portion 32a and a bottom portion 32b secured together by a suitable fastening means 34 (Fig. 5).

Partition means in the form of a tubular member 35 are provided for restricting the exhaust from the pump to the space on one side of the piston and the intake to the space on the opposite side of the piston. As shown, the upper end of the tubular member 35 is secured to the

platform 14 by any suitable fastening means whilst its lower end is provided with a flange 36 either formed integrally with the upper portion 32a of the inside tank or connected thereto by suitable fastening means. The lower portion 32b of the inside tank is formed integrally with a tubular member 37 which may be regarded as an extension of the tubular member 35. This extended portion 37 is suitably secured in the bottom wall of the outside tank 10 and it is provided with a flange 38 spaced from the flange 36 to provide a space within which the pump housing 18 is mounted for rotation between two limiting positions. A lower circumferential fluid chamber 39 is formed by the flange 38 and the cupped portion 32b of the inside tank.

A vertical drive shaft 40 is rotatably mounted in a bearing 41 in the supporting platform 14 and in a bearing 42 centrally mounted within the tubular extension near the bottom of the fluid container. This drive shaft 40 is connected to the motor shaft 13 by suitable coupling means 43 and the impeller 19 is keyed to the shaft 40 so as to rotate therewith when the pump driving motor 12 is energized. In order to rotate the housing between its two limiting positions, suitable actuating means are provided. These means are illustrated as comprising a pin 44 passing through the plates 20 and 21 of the housing, a slotted member 45 engaging with the pin and a vertical spindle 46 extending upwardly through the cover plate 11. A manually operated handle 47 is illustrated as being provided for rocking the shaft 46 so as to move the housing between its two limiting positions. It will be understood, however, that any other suitable means such for example as a pair of solenoids or a single solenoid and a spring may be utilized instead. The handle 47 is shown merely for simplicity.

In Fig. 4 the housing 18 is shown in one of its limiting positions which is denoted as position A, whilst in Fig. 3 the housing is shown in the other of its limiting positions which is denoted as position B. It will be observed that in position B the housing member is rotated through an angle in a clockwise direction from position A. In the embodiment illustrated in the drawings, this angle is approximately 22½°.

Within the tubular member 35 is a stationary member 48 which is provided with a plurality of openings or passages 49 and similarly the lower portion 37 of the tubular member is provided with a plurality of circumferential openings or passages 50. The passages 49 and 50 register respectively with intake ports 26 and 29 when the housing is in position A, whereas intake ports 26 and 29 are covered when the housing is in position B. Likewise, the flange 38 of the tubular member is provided with a circumferential row of openings or passages 51 which register with the exhaust ports 30 when the housing is in position A. In addition the tubular member 35 is provided with a circumferential row of passages 52 whilst the lower portion 37 of the tubular member is provided with a similar row of circumferential passages 53. The passages 52 and 53 register respectively with intake ports 27 and 28 when the housing is in position B. Near the lower extremity of the upper portion of the inside tank member 32a, is a row of circumferential openings or passages 54 which lead into the passageway 33 and which register with the exhaust ports 31 when the housing is in the position B.

It will thus be seen that the housing member

18 of the pump is a rotary valve mechanism for controlling the flow of fluid to one side or the other of the piston 15 and thus to cause it to move in the desired direction.

In addition to the ports and passages already described, it will be observed that the pump housing is provided with a pair of channels 55 and 56 arranged diametrically opposite each other and passing through the housing including both top and bottom plates 20 and 21. The openings of these channels 55 and 56, respectively in the top plate are clearly visible in Fig. 5. As shown, the flange 38 of the lower tubular portion 37 is provided with openings or passages 55a and 56a which register respectively with the channels 55 and 56 when the housing is in position B.

With the above understanding of the structure and arrangement of the various ports and passages, the operation of the device itself will readily be understood from the following detailed description:

Assuming the piston 15 to be at the bottom of its stroke as illustrated in Fig. 1 and the pump housing to be in the position A, energization of the motor 12 by connection to a source of electric power produces rotation of the drive shaft 40 and the impeller 19. Fluid is directed from the space above the piston 15 through the passages 57 in the tubular member 35, thence downwardly through the tubular member, through passages 49 and intake ports 26 to the impeller. Fluid is also drawn downwardly through the passage 33 between the inner tank and outer container, through passages 50 and intake ports 29 and thence axially upwardly to the impeller.

Since fluid is directed axially in both directions into the central intake of the impeller, end thrust is eliminated. From the impeller 19, fluid 40 is discharged radially outwardly into the pressure chamber 23 and thence upwardly through exhaust ports 30 and passages 51 to the space beneath the piston. As a result, the fluid pressure against the lower surface of the piston is increased thereby producing a differential fluid pressure which causes the piston 15 to move upwardly. This pressure and movement are transmitted through the connecting rods 16 to the external load to which the cross-head 17 is connected.

When the piston 15 reaches the upper limit of its stroke, this differential fluid pressure across the piston is maintained, but not increased due to the fact that the impeller pump 55 is not a positive displacement pump.

In order to reverse the direction of the differential fluid pressure across the piston and return the piston to its initial position at the lower end of its stroke, the handle 47 is moved 60 to shift the pump housing 18 from position A to position B. As illustrated in Fig. 2 the passages 49, 50 formerly in register with intake ports 26 and 29, respectively, and the passages 51 formerly in register with exhaust ports 30 65 are now covered. Fluid is now drawn from the space beneath the piston through passages 52 and intake ports 27 in register therewith, and thence axially downwardly into the impeller. Simultaneously fluid is drawn from the space 70 beneath the piston through passages 55a and 56a in the flange 38 and the channels 55 and 56 in register therewith through passages 55b and 56b in the flange 38 to the chamber 33 in the lower end of the inside tank beneath the 75

pump housing, thence through passages 53 and intake ports 28 and thence axially upwardly to the intake of the impeller. From the impeller fluid is discharged radially outwardly to the 5 pressure chamber 23 and thence radially outwardly through exhaust ports 31 and passages 54 in register therewith, upwardly through the fluid passage 33 between the inside tank 32 and the outside container 10 to the space above 10 the piston. As a result, the fluid pressure against the lower face is decreased, and the resulting differential fluid pressure on opposite sides of the piston causes the latter to move downwardly until it again arrives at the lower 15 end of its stroke as illustrated in Fig. 2. Operation of the handle 47 to shift the housing from position B to position A will produce upward movement of the piston in the manner previously described.

20 In the modification of Fig. 6, a plurality of ducts 59 lead from the tubular member 60 to a manifold 61 surrounding the pump housing 62. A second plurality of ducts 63 communicate with the space beneath the piston 64 by means 25 of passages 65 in the flange 66 and channels (not shown) through the pump housing 62.

The ducts 59 and 63 take the place respectively of the fluid passageway 33 and chamber 39 of the structure of Fig. 1, thereby eliminating the necessity of the inner tank 32 of Fig. 1. Consequently but a single container 67 serving both as the fluid container and the operating cylinder for the piston is required. The remainder of the structure and the arrangement 35 of the ports and passages is otherwise identical with the corresponding features in the structure of Fig. 1, and repetition of the description is, therefore, unnecessary.

In operation with piston 64 at the bottom 40 of its stroke fluid is drawn from the space above the piston 64 through the tubular member 60 and intake ports 68 to the intake of the impeller and also from the tubular member 60 through the ducts 59 through the intake 45 port 69 and thence upwardly to the intake of the impeller. Fluid is discharged radially outwardly from the impeller and upwardly through the exhaust ports 70 to the space beneath the piston. The differential pressure thus produced on opposite sides of the piston causes the latter to move upwardly.

The return or downward stroke of the piston is accomplished by shifting the pump housing from the position A to position B thereby closing the ports previously mentioned. Fluid is 55 then drawn from the space beneath the piston through passages 65, channels (not shown) in housing 62, ducts 63 and thence axially upwardly to the intake of the impeller. Likewise fluid is drawn through intake ports 71 and 60 axially downwardly to the intake of the impeller. From the impeller fluid is discharged radially outwardly through circumferential exhaust ports into the manifold 61 and thence 65 upwardly through the ducts 59, into the tubular member 60 and thence to the space above the piston 64. As a result, the direction of the differential fluid pressure across the piston is reversed and the latter is caused to move downwardly. This operation is repeated as often as the rotary valve means, i. e., the pump housing 70 is shifted between its limiting positions A and B.

Although in accordance with the provisions 75 of the patent statutes, this invention is de-

scribed as embodied in concrete form, it will be understood that the operating elements, ports and fluid passages are merely illustrative and that the invention is not limited thereto since alterations and modifications will readily suggest themselves to persons skilled in the art without departing from the true spirit of this invention or from the scope of the annexed claims.

What I claim as new and desire to secure by Letters Patent of the United States is:

1. A double acting hydraulic operating mechanism composing a fluid container, a piston movably mounted therein, an impeller pump mounted in said container, a tubular member 15 having spaced apart flanges to provide a space for said pump and having passages leading to both sides of said piston, a housing member for said impeller pump mounted in the space between said flanges for rotation between two 20 limiting positions and provided with intake and exhaust ports, certain of said ports being arranged to register with certain of said passages when said housing is in one of said positions to effect movement of said piston and certain of 25 said ports arranged to register with certain of said passages in the other position of said housing to effect reverse movement of said piston, and means for actuating said housing from one of said positions to the other. 30

2. A double acting hydraulic operating mechanism comprising a fluid container, a piston movably mounted therein, an impeller pump mounted within said cylinder for producing a differential fluid pressure on opposite sides of said piston to 35 effect movement thereof, partition means comprising a tubular member having spaced apart flanges to provide a space for said pump and having at least a pair of passages leading to each side of said piston, a housing for said impeller rotatably mounted in the space between 40 said flanges and having intake and discharge ports, one of each of said pairs of passages being arranged to register with an intake port and with an exhaust port respectively when said 45 housing is in one of said positions to effect movement of said piston in one direction, and the other of each of said pairs of passages being arranged to register with an intake and an exhaust port respectively when said housing is in 50 said other position to effect movement of said piston in the opposite direction and means for effecting movement of said housing from one of said positions to the other.

3. A double acting hydraulic operating mechanism comprising a cylindrical fluid container, a piston movably mounted therein, an impeller pump for producing a differential fluid pressure on opposite sides of said piston to effect movement thereof, partition means comprising a tubular member having spaced apart flanges to provide a space for said pump, said tubular member having at least two passages leading to one side of said piston and one of said flanges having at least two passages leading from said 65 space to the other side of said piston, a housing for said impeller mounted in said space for rotation between two limiting positions, said housing having an intake port arranged to register with one of said passages leading to said 70 one side of said piston and an exhaust port arranged to register with one of said flange passages when said housing is in one of said positions and having a second exhaust port arranged to register with another of said passages 75

leading to said one side of said piston and a second intake port arranged to register with the other of said flange passages, and means for moving said housing from one of said positions 5 to the other to effect movement thereof in opposite directions.

4. A double acting hydraulic operating device comprising a cylindrical fluid container, a piston mounted for longitudinal movement therein, 10 an impeller mounted in said container beneath said piston for producing a differential fluid pressure on opposite sides of said piston to effect movement thereof, partition means comprising a centrally disposed tubular member having 15 passages providing communications from the space on one side of said piston and having a pair of flanges spaced apart to provide a space for said impeller and provided with passages affording communication from the exhaust of 20 said impeller to the space on the other side of said piston, and rotary valve means comprising a housing for said impeller mounted in said space and having passages adapted to register with the passages in said tubular member and 25 in said flange for reversing said communications to effect reversal of the movement of said piston.

5. A double acting hydraulic operating mechanism comprising a fluid container, a piston movably mounted therein, an impeller pump 30 mounted in said container comprising a rotatably mounted impeller and a housing therefor mounted for movement between limiting positions, said housing being provided with a plurality of intake ports and a plurality of exhaust 35 ports, a tubular member having spaced apart flanges to provide a space for said pump and having a plurality of passages leading to one side of said piston and a plurality of passages leading to the opposite side of said piston, cer- 40 tain of said intake ports and exhaust ports being arranged for register with certain of said pluralities of passages when said housing is in one of said positions and others of said intake and exhaust ports being arranged for register 45 with others of said pluralities of passages when said housing is in the other of said positions, and means for moving said housing from one of said positions to another to reverse the move- 50 ment of said piston.

6. A double acting hydraulic operating mechanism comprising a fluid container, a piston movably mounted therein, means for producing a differential pressure on opposite sides of said piston to effect movement thereof comprising a 55 rotatably mounted impeller and a housing therefor operable between limiting positions and provided with an exhaust port and with a pair of central intake ports for supplying fluid in opposite directions to said impeller, partition 60 means including a tubular member having flanges spaced apart to provide a space for said housing and having a plurality of passages including a passage through each of said flanges leading to one side of said piston and a plurality 65 of passages leading to the other side of said piston, one of said intake ports being arranged to register with one of the passages leading to one side of said piston and a channel through said housing arranged to register with said 70 flange passages to establish communication from said one side of said piston to the other of said intake ports when said piston is in one of said positions and means for moving said housing from one of said positions to the other.

7. An hydraulic operating mechanism com-

prising a fluid container, a piston movably mounted therein, means for producing a differential fluid pressure on opposite sides of said piston to effect movement thereof comprising a rotatably mounted impeller and a housing there- 5 for arranged for movement between limiting positions, said housing being provided with a plurality of central intake ports on each side of said impeller and with a plurality of exhaust ports, partition means including a tubular mem- 10 ber having flanges spaced apart to provide a space for said housing, a plurality of passages through said flanges leading to one side of said piston, a plurality of passages through said tu- 15 bular member leading to each side of said piston, certain of said intake ports being arranged to register with certain of said passages leading to said one side of said piston and certain of said exhaust ports being arranged to register with certain of said passages leading to the 20 other side of said piston, and others of said intake and exhaust ports arranged to register with others of said passages when said housing is moved to another position, a channel through 25 said housing arranged to register with a passage in each of said flanges to establish communica- 30 tion between one of said intake ports to said one side of said piston when said housing is in said first position, and means for moving said housing from one of said positions to the other.

8. A double acting hydraulic operating mechanism comprising a fluid container, a tank open at one end and immersed in the fluid in said container, a piston movably mounted in said tank, an impeller for producing a differential in the fluid pressure on opposite sides of said piston to effect movement thereof comprising a rotatable impeller and a housing therefor ar- 35 ranged for movement between two positions and provided with a plurality of exhaust ports and a plurality of intake ports, a tubular member with- 40 in said tank having spaced apart flanges to provide a space for said housing, the wall of said tank being spaced from the wall of said container to provide a fluid passage leading to one side of said piston, said tubular member having an opening leading to the opposite side of said piston and arranged to register with one of said intake ports and said tank having an opening 45 arranged to register with one of said discharge ports when said housing is in one position thereby to effect movement of said piston in one direction, said tubular member having additional openings leading to both sides of said piston and arranged when said housing is in a second position to register with exhaust and intake ports 50 to effect reverse movement of said piston.

9. A double acting hydraulic operating mechanism comprising a fluid container, a piston movably mounted therein, a pump mounted in said container for producing a differential pressure on opposite sides of said piston comprising a rotatable impeller and a housing movable between two positions and provided with intake 60 and exhaust ports, means for driving said im- 65 peller, partition means comprising a tubular member leading to one side of said piston and provided with an opening through the wall there- 70 of arranged to register with an intake port and means connecting an exhaust port with the opposite side of said piston when said housing is in one of said positions thereby to effect move- 75 ment of said piston, a duct leading from said tubular member to an exhaust port and ar-

ranged to register therewith when said housing is in a second position, said tubular member being provided with an additional opening leading to said opposite side of said piston and arranged to register with an intake port when said housing is in said second position thereby to effect reverse movement of said piston, and means for effecting movement of said housing between said positions.

10. A double acting hydraulic operating mechanism comprising a fluid container, a piston movably mounted therein, a pump immersed in the fluid comprising a rotatable impeller and a housing therefor movable between two limiting positions, driving means for rotating said impeller to produce a differential fluid pressure on opposite sides of said piston to effect movement thereof, partition means comprising a tubular member having spaced apart flanges providing a space for said housing, said tubular member having openings leading to both sides of said piston and said flanges having openings leading to one side of said piston, a duct leading from said housing to said tubular member, said housing having an intake port on one side of said impeller arranged to register with an opening in said tubular member leading to one side of said piston and an intake port on the opposite side of said impeller arranged to register with an opening leading through said duct to said one side of said piston and an exhaust port arranged to register with an opening in said flange leading to the opposite side of said piston when said housing is in one of said positions, thereby to effect movement of said piston in one direction, said housing having additional intake ports on each side of said impeller arranged to register with openings in said tubular member leading to said opposite side of said piston and provided with additionally an exhaust port ar-

ranged to register with an opening in said duct leading to said one side of said piston, thereby to reverse the movement of said piston.

11. A double acting hydraulic operating mechanism comprising a fluid container, a cylindrical member open at one end immersed in the fluid within said container, a piston movably mounted in said cylindrical member, the walls of said container and cylindrical member being spaced apart to provide a fluid passageway leading to the space on one side of said piston, a longitudinally extending tubular member within said cylindrical member provided with separated flanges extending outwardly to said cylindrical member to form a space and having a plurality of openings leading to said one side of said piston and a plurality of openings leading to the opposite side of said piston, said cylindrical member having openings in the wall thereof leading from said passageway to said space, an impeller, a rotatably mounted housing therefor mounted in said space for movement between limiting positions, said housing being provided with a plurality of intake ports and a plurality of discharge ports, certain of said intake ports being arranged to register with certain of said openings leading to said one side of said piston and certain of said discharge ports being arranged to register with certain of said openings leading to said opposite sides of said piston when said housing is in one of said positions, and others of said discharge ports being arranged to register with said openings in said cylinder wall and certain of said intake ports being arranged to register with certain of said openings leading to said opposite sides when said housing is in the other of said positions, and means for moving said housing from one of said positions to the other.

THEODORE W. DRIESCH. 40

CERTIFICATE OF CORRECTION.

atent No. 2,036,797.

April 7, 1936.

THEODORE W. DRIESCH.

It is hereby certified that error appears in the printed specification of the above numbered patent requiring correction as follows: Page 3, second column, line 13, claim 1, for the word "composing" read comprising; and that the said Letters Patent should be read with this correction therein that the same may conform to the record of the case in the Patent Office.

Signed and sealed this 26th day of May, A. D. 1936.

Leslie Frazer
